UNITED STATES PATENT OFFICE.

CHARLES GULDEN, OF NEW YORK, N. Y.

DESIGN FOR A BOTTLE.

SPECIFICATION forming part of Design No. 28,412, dated March 29, 1898.

Application filed November 1, 1897. Serial No. 667,110. Term of patent 14 years.

To all whom it may concern:

Be it known that I, CHARLES GULDEN, a citizen of the United States, residing at New York, in the county and State of New York, have invented and produced a new and original Design for a Bottle, of which the following is a specification, in which reference is had to the accompanying drawings, forming part thereof.

10 In the drawings, Figure 1 is a perspective view of a bottle embodying my design. Fig. 2 is a transverse section of the same on the line 2 2 of Fig. 1.

15 The characteristic features of my design are essentially those represented in the accompanying drawings.

In the accompanying drawings, A repre-

sents the main body portion of the bottle, which is made up of plain concave sides *a*, joining plain flat corners *b*. This body portion is surmounted by a plain neck which has the general appearance of being cylindrical in form, but which, in fact, slightly tapers inwardly toward the bottom, where it joins a plain concave portion *c*, that unites the neck 25 to the body portion.

What I claim is—

The design for a bottle, substantially as herein shown and described.

CHARLES GULDEN.
